[57] ABSTRACT

A cassette for housing a coiled elongated flexible electrically conductive knife blade which is withdrawn therefrom through an opening at one end. A resilient spring is biased against the knife blade to complete a circuit through the knife blade so that the cassette can be installed in a circuit that will indicate when the knife blade is exhausted.

CASSETTE FOR COILED KNIFE BLADE

This patent application is a continuation-in-part of co-pending U.S. Pat. application Ser. No. 774,720 filed Nov. 12, 1968, now U.S. Pat. No. 3,545,322.

This invention relates to a cassette for a coiled knife blade and more particularly to a cassette for a coiled knife blade of the type that can be mounted on a machine.

In many manufacturing processes wherein materials such as motion picture film, magnetic film, paper, plastics and the like are manufactured in running lengths it is necessary to divide or cut the sheet into sections of reduced width. This is achieved by providing slitting knives having blades which are disposed at regular intervals transversely of the direction of movement of the material. Because the material moves rapidly past the knife blades, such blades are quickly dulled and it becomes necessary to provide a mechanism for regularly advancing into the cutting zone fresh sections of the knife blade. An apparatus for achieving this is disclosed in the above-noted patent application. However, there has never been a satisfactory way of storing that portion of the knife blade which has not yet been used nor has there been any successful way achieved of indicating that the knife blade is exhausted.

Accordingly, it is an object of this invention to provide a cassette for housing a coiled slitting strip knife blade.

It is a further object of this invention to provide a cassette for housing a coiled slitting strip knife blade wherein the blade is part of an electric circuit which indicates when the blade is exhausted.

It is a still further object of this invention to provide a housing for a coiled slitting blade wherein means are provided on the cassette for mounting the cassette on a machine with the proper orientation.

Generally the invention relates to a cassette for an electrically conductive coiled strip knife blade comprising a housing. The housing is closed at one end to define a chamber for the coiled knife blade and has an aperture at its other end through which an end of the coiled knife blade is adapted to be drawn for advancing the knife blade into the path of the material to be cut. Electrically conductive means is supported by the housing so that it is adjacent the aforementioned aperture and so that it is in engagement with the knife blade as it is withdrawn from the housing so that an electric circuit can be completed through the electrically conductive means and the knife blade.

Other objects and advantages of the subject invention will become apparent from a detailed description of a preferred embodiment thereof which is illustrated in the accompanying drawings wherein:

FIG. 1 is a perspective view of a cassette constructed in accordance with a preferred form of the invention with a portion of a knife blade depending therefrom;

FIG. 2 is a plane view of the cassette illustrated in FIG. 1 with the top cover removed therefrom;

FIG. 3 is a sectional view of the cassette taken along line 3-3 of FIG. 2;

FIG. 4 is a sectional view of the cassette taken along line 4-4 of FIG. 2; and

FIG. 5 is a schematic circuit diagram showing how the cassette can be connected to an electric circuit.

Referring to the drawings in detail it can be seen that the cassette 10 houses the coiled knife blade 12 so that a portion of it depends from the cassette. The cassette

comprises a generally U-shaped outer flange member 13 which is supported on a base 14 housed therein. Molded integrally with the base and flange is a first guiding portion 15 having a concave surface 16 that cooperates with a second portion 18 integrally molded with the base and flange that provides a second concave surface 19. First and second concave surfaces 16 and 19 cooperate with the rounded portion of U-shaped flange 13 to provide a chamber.

At the opposite end of the housing the first and second integral portions present opposing faces 21 and 22 which are spaced slightly from each other to define an elongated, substantially rectangular aperture 25. A coiled knife blade 28, of the type which is more completely described in the above-mentioned co-pending patent application, is positioned in the above-mentioned chamber with its free end 30 depending downwardly through elongated aperture 25 so that it can be advanced toward the cutting zone.

Means may be provided for resiliently urging the end of the knife blade 30 against face 21 when the cassette is mounted in its operative position. Preferably such a means takes the form of a spring member 34 which may be of S configuration. The spring member may be housed in an elongated recess 32 which is disposed laterally of and which is in communication with elongated aperture 25. Such a spring preferably presents a relatively flat smooth surface 35 that can be moved into engagement with the knife blade. While an S-shaped spring is preferred, it is to be understood that any other type of restraining means may be employed providing it has the same general characteristics as the preferred S-shaped spring.

The housing also includes two elongated recesses 36 and 37 which are parallel to the elongated aperture 25 and which are disposed on opposite sides thereof. These recesses, which are employed to mount the cassette on a suitable mounting device are of different sizes to accommodate different size pins so that the cassette will always have the proper orientation.

It should be noted that one end of the aforementioned S-shaped spring 34 extends slightly into recess 36 so that when a pin is inserted therein the spring is pressed to the right, into engagement with the blade (FIG. 2) as mentioned above. The housing includes a cover 42 which is received within the U-shaped flange 13 and may be fixed thereto to close off the housing.

Additionally, if desired, the housing can be fabricated with aligned apertures 44 and 45 in the cover and base so that an auxiliary means for mounting the cassette can be provided or, in the alternative the cassette can be stored on a thin rod which is passed through the apertures.

Operation of the device is achieved by merely grasping the end 30 of the knife blade with a suitable tool and withdrawing it from the housing against the force of spring 34. Naturally, that portion of the spring which is in engagement with the blade should not have anything on its surface which would scratch or in any other way mar the side of the blade.

Under some circumstances it is preferred that a warning be provided when the blade has been exhausted from the housing and a replacement blade is necessary. A warning device can be provided with the subject cassette when it is connected to a machine with a circuit of the type schematically illustrated in FIG. 5. In that figure a source of electromotive force 47 is con-

nected by an of-off switch 48 to a circuit comprised of lines L₁ and L₂ wherein it is in parallel with the branch having the machine on-off light 51, the machine motor 53, branch 65 having the knife blade exhaust light 58 and branch 67 having the cassette. Line L₁ also includes an element having a high impedance such as a resistor 59. Capacitors 62 in lines L₁ and L₂ are provided to reduce any possible shock hazard that might accompany use of this device.

It should be noted that the cassette is electrically interconnected to the circuit by pin 63 which is inserted in aforementioned recess 36. Spring 34, which is made of electrically conductive material is urged into engagement with knife blade 30 by pin 63 so that it completes an electrical circuit therewith. The knife blade is in contact with a suitable brush 61 which is connected to line L₂. The brush may be a portion of the machine.

Thus, when switch 48 is closed the machine 53 begins to operate and light 51 goes on indicating such operation. Impedance 59 assures that only a very small voltage will be available across the indicator and cassette branches. Normally electrical current generated by this voltage will run through pin 63, spring 34, the knife blade 30 and brush 61. Knife exhaust light 58 is bypassed because of the cassette has relatively low impedance compared to the light 58. However, when the knife blade is exhausted the circuit through cassette branch 67 will open and current will then flow through impedance 59 and light 58 indicating that the cassette is empty.

Additionally, it should be noted that in normal use a plurality of cassettes of the type described are used and they are set at regularly spaced intervals transversely of the direction to which the material to be cut is moving. In this regard it should be apparent that the circuit which would include such additional cassettes is similar to that illustrated in FIG. 5 in that for each cassette used there would be a branch 55 and a branch 67 extending between lines L₁ and L₂.

While the invention has been described with reference to a particular embodiment thereof which has been set forth herein, the scope of the invention should not be limited by the foregoing description but rather, only by the scope of claims appended hereto.

We claim:

1. A cassette for housing a coiled elongated flexible knife blade comprising a base member, said base member having two portions with facing concave surfaces that define a circular housing for said coiled knife blade, said portions being spaced from each other to define an elongated aperture connecting said circular housing with the outside of said cassette, each of said portions being provided with elongated recesses, said recesses being of different sizes and disposed on opposite sides of said aperture, and said blade being coiled in said housing and having an end adapted to be withdrawn through said aperture.
2. A cassette as defined in claim 1 including an elongated opening connecting one of said elongated recesses and said aperture.
3. A cassette as defined in claim 2 including resilient means disposed in said elongated opening, said resilient means having two ends, one end of said resilient means extending into said one elongated recess when the other end of said resilient means extends into said elongated aperture.
4. A cassette for housing a coiled elongated flexible knife blade comprising a base member, said base member having two portions with facing concave surfaces that define a circular housing for said coiled knife blade, said portions being spaced from each other to define an elongated aperture connecting said circular housing with the outside of said cassette, each of said portions being provided with an elongated recess on opposite sides of said aperture, and said blade being coiled in said housing and having an end adapted to be withdrawn through said aperture.
